SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY

WATER-COOLING DEVICE FOR COMPRESSORS

Application filed December 3, 1927. Serial No. 237,445.

This invention relates to compressors, but more particularly to a water cooling device connected to the water jacket of the compressor cylinder and adapted to shut off the supply 5 of cooling water to the water jacket simultaneously with the starting and stopping of the compressor.

It is an object of the invention to prevent the wasteful discharge of cooling water 10 through the water jacket of the compressor while the compressor is idle.

Another object of the invention is to insure an adequate supply of cooling water to the compressor cylinder at the beginning of the 15 loaded period of the compressor.

Other objects will be in part obvious and in part pointed out hereinafter and to all of these ends the invention consists of the features of construction and arrangement of 20 parts having the general mode of operation substantially as hereinafter described and claimed and illustrated in the accompanying drawing, in which is shown a compressor cylinder in longitudinal sectional elevation 25 having the invention applied thereto.

Referring more particularly to the drawing, A designates a portion of a double acting compressor having a cylinder B in which is disposed a piston C. The piston C is provided 30 with the usual piston rod D which extends slidably through a head E on one end of the cylinder and may be connected to a suitable prime mover (not shown) in a well known manner. A head F forms a closure for the 35 opposite end of the cylinder B and in these heads E and F are suitable chambers G which, in conjunction with a chamber H encircling the cylinder B intermediate its ends, constitute the water jacket for the cylinder.

40 At opposite ends of the cylinder B are the usual inlet valves J through which the air intended to be compressed may enter the cylinder. At these points of the cylinder also are the discharge valves K through which the compressed air may pass into a discharge chamber L forming a part of the cylinder. The air thus discharged into the chamber L may pass through a discharge opening O connected with a receiver tank P by a pipe Q.

45 In the wall of the cylinder B is an inlet

opening R through which the atmospheric air intended to be compressed may pass to the inlet valves J. The inlet opening R in this instance is controlled by an unloader valve generally designated by S and comprising 55 a hollow casing T in which are formed ports U and V. The ports U and V in addition to their function of admitting air into the casing S also act as a guide for a valve W which co-operates with the ports U and V for controlling 60 the intake supply to the compressor. Acting on one end of the valve is a spring X which seats with its other end against a set screw Y threaded into the casing S for adjusting the tension of said spring X. 65

In its open position the valve W seats against a cylinder Z which forms an integral part of a cover b attached to the casing T. In the cylinder Z is disposed a piston c against which pressure fluid may act for closing the 70 valve W.

Suitable means are provided for automatically cutting off the supply of cooling water from the water jacket of the cylinder B and which cooling water is conveyed to the water 75 jacket through a pipe d communicating in this instance with the chamber H. These means consist of a water valve e interposed in the pipe d and comprises a casing f in the lower end of which are a pair of chambers g 80 and h divided by a wall k. A port o is formed in the wall k to afford communication between the chambers g and h. At the lowermost end of the port o is a valve seat p for a valve q reciprocable in the port o. The valve 85 q is of the poppet type and has an upwardly extending stem r on which is disposed a piston s slidable in the uppermost end of the casing f.

In the piston s is a chamber t for the reception of a spring u which acts with its uppermost end against the piston and with its lowermost end against a shoulder v in the casing f for actuating the piston s in an upwardly direction to close the valve q. At 95 the uppermost end of the piston s is formed a tapered surface w which cooperates with a correspondingly tapered seat x in the casing f to prevent leakage of pressure fluid past the piston into the casing f. A cover y 100

is secured to the top of the casing *f* and has a chamber *z* into which pressure fluid may be admitted for depressing the piston *s* and thus open the valve *q*.

5 Pressure fluid for actuating the piston *s* is conveyed to the chamber *z* through a pipe 2 connected at one end to the cover *y* and with its other end to a pipe 3. The pipe 3 may be said to be in the form of a loop and communicates at its front and rearward ends with the corresponding ends of the piston *C* through check valves 4 and 5 respectively. The check valves may be connected to the usual indicator holes of the cylinder *B* and 10 consist of cup shaped valves 6 reciprocable in casings 7. Springs 8 disposed between the valves 6 and covers 9 threaded into the casings 7 tend to maintain the said valves in closed position.

20 The valves 6 serve to admit pressure fluid from the cylinder *B* into the pipe 3 but are so disposed with respect to the indicator ports of the cylinder that they will not admit air into the cylinder on the suction stroke of the 25 piston *C*.

Interposed in the pipe 3 is a relief valve 10 consisting of a casing 11. In the upper end of the casing is a passage 12 which forms a connection between the sections of the pipe 3. 30 In the passage 12 is a depending annular flange 13 which acts as a guide for a ball valve 14 adapted to control a port 15 in the casing 11. The ball valve 14 is normally held closed by a spring 16 and controls communication 35 between the passage 12 and atmospheric ports 17 in the casing 11.

The lower portion of the casing 11 is in 40 the form of a cylinder 18 in which is disposed a piston 19 normally held in retracted position by a spring 20. The spring 20 is preferably disposed in the piston 19 and acts with its uppermost end on a wall 21 in the casing 11. A plunger 22 which may be secured with its lowermost end to the piston 19 extends with 45 its other end against the ball valve 14.

The admission of pressure fluid into the cylinder 18 for actuating the piston 19 is preferably effected in synchronism with the stopping of the prime mover or with the unloading of the compressor. The means for accomplishing this in the present instance consists of an auxiliary valve 23 of a well known type having suitable valve mechanism for controlling communication between the pipe 24 leading from the auxiliary valve 23 to the receiver tank *P*, and a pipe 25 leading from the auxiliary valve to the relief valve 10.

While, as before stated, the valve mechanism of the auxiliary valve 23 is not shown, 60 its position is indicated by a stem 26 which projects from the lowermost end of the auxiliary valve 23 and rests on a lever 27 pivoted on the foot of the auxiliary valve 23. A terminal 28 of the lever 27 may be pivotally connected to an armature 29 of an electro-magnet

30 attached in this instance to the auxiliary valve 23. 31 and 32 designate wires which lead from the electro-magnet 30 to a switch (not shown) whereby the starting and stopping of the prime mover for the compressor 70 may be controlled.

The pipe 25 leading from the auxiliary valve 23 to the relief valve 10 may be extended to supply pressure fluid to the cylinder *Z* of the unloader valve *S* simultaneously with the admission of pressure fluid to the relief valve. Preferably a hollow casing 33 is interposed between the pipe 25 and the cylinder *Z* to form a reservoir for pressure fluid adjacent 75 the piston *C*.

In the normal operation of the device, while the compressor *A* is operating under full load conditions, the valves *W* and *q* will occupy their open positions, and the relief valve will remain closed while the auxiliary valve will 80 occupy a position to prevent communication between the pipes 24 and 25.

When operating under full load conditions, air drawn into the cylinder *B* through the inlet opening *R* will be compressed and discharged into the discharge chamber *L* from whence it may pass through the discharge opening *O* and the pipe *Q* into the receiver tank *P*. At the same time pressure fluid will flow through the check valves 4 and 5 and the pipes 3 and 2 into the chamber *z* of the water valve *v* and, acting against the piston *s*, will depress said piston and thus hold the valve *q* open. In this position of the valve *q* water may flow through the pipe *d* into the water jacket. Such supply of cooling water may continue uninterruptedly to the water jacket as long as air is being compressed in the cylinder *B*.

Whenever the starting switch of the motor which drives the compressor is opened to stop the motor, the electro-magnet 30 will become deenergized. This will enable the armature 29 to drop and automatically open the auxiliary valve 23 in a well known manner to 105 admit pressure fluid from the pipe 24 into the pipe 25 and thus to the cylinder *Z* for closing the valve *W* in order to cut off the intake supply to the cylinder *B*.

Upon the admission of pressure fluid to the unloader valve *S*, a portion of pressure fluid will flow into the cylinder 18 of the relief valve 10 and will force the piston 19 upwardly against the spring 20 to unseat the ball valve 14. In this way the pressure fluid utilized for opening the valve *q* will be exhausted to the atmosphere and said valve *q* will then be returned to its closed position by the springs *u* and *q'* acting against the piston *s* and the valve *q* respectively.

The ball valve 14 will be held open as long as pressure fluid remains in the pipe 25, that is, as long as the compressor remains idle and during the starting and stopping periods. Such being the case, any air which may leak 130

into the cylinder B will be expelled therefrom through the check valves 4 and 5, the pipe 3 and thence through the ports 15 and 17 to the atmosphere. By permitting the water valve *q* to close at the instant of unloading of the compressor, the supply of cooling water to the chambers of the water jacket will be immediately shut off. In this way is effected a considerable saving in the expense 10 of operating the compressor. This is particularly advantageous in localities where a free supply of cooling water is not available and where the cooling water to the compressor is metered and paid for accordingly.

15 During the idle and starting periods of the compressor, the electro-magnet 30 will remain deenergized and consequently the auxiliary valve 23 will occupy its open position to admit pressure fluid to the various unloading devices of the compressor, thus minimizing the starting load on the compressor motor. When the compressor approaches its maximum speed and the motor control switch is moved into position to admit full line current to the motor, the electro-magnet 30 will again become energized and allow the valve 23 to close and cut off communication between the pipes 24 and 25. The pressure fluid in the pipe 25 and the casing 33 will then 25 escape through the auxiliary valve 23 to the atmosphere in a well known manner and permit the valve *W* to open under the influence of the spring *X*. At the same time the ball valve 14 will return to its seat and cut off 30 communication between the pipe 3 and the ports 17. The air discharged into the pipe 3 from the cylinder B will then flow into the chamber *z* and, acting against the piston *s*, will open the valve *q* to again admit water 35 into the water jacket.

40 I claim:

1. In a compressor, the combination of a cylinder having inlet and discharge openings, a receiver tank connected to receive pressure fluid discharged from the cylinder, a water jacket on the cylinder, a water valve, a pipe connected to the ends of the cylinder for conveying pressure fluid from the cylinder to the water valve for holding said water valve open during the operation of the compressor, and a relief valve interposed in the pipe adapted to remain closed during the normal operation of the compressor and actuated by receiver pressure for venting the cylinder and the water valve to the atmosphere during the time the compressor is operating at less than normal speeds, thus preventing the compression of air leaking into the cylinder as well as the flow of water into the water jacket.

60 2. In a compressor, the combination of a cylinder having inlet and discharge openings, a receiver tank connected to receive pressure fluid discharged from the cylinder, a water jacket on the cylinder, a water valve, a pipe 65 conveying pressure fluid from the ends of

the cylinder to the water valve for holding said water valve open during the operation of the compressor, and a relief valve interposed in the pipe adapted to remain closed during the normal operation of the compressor and to be constantly held open by receiver pressure during the unloaded period of the compressor for venting the cylinder and the water valve to the atmosphere, thus preventing the compression of air leaking into the cylinder and also preventing the flow of cooling water into the water jacket.

70 3. In a compressor, the combination of a cylinder having inlet and discharge openings, a receiver tank connected to receive the discharge from the cylinder, a water valve controlling the flow of water into the water jacket, a pipe connected to the ends of the cylinder to convey pressure fluid to the water valve for holding said water valve open during the operation of the compressor, and a relief valve interposed in the pipe adapted to remain normally closed and to be constantly held open by receiver pressure during the inoperative period of the compressor to prevent the compression of air leaking into the cylinder as well as to prevent the flow of cooling water into the water jacket.

75 4. In a compressor, the combination of a cylinder having inlet and discharge openings, a receiver tank connected to receive the discharge from the cylinder, a water valve controlling the flow of water into the water jacket, a pipe connected to the ends of the cylinder to convey pressure fluid directly from the cylinder to the water valve for holding said water valve open during the operative period of the compressor, a relief valve interposed in the pipe and constantly held open by receiver pressure during the starting, stopping and idle periods of the compressor to prevent the compression of air leaking into the cylinder as well as to prevent the flow of cooling water into the water jacket, and check valves in the pipe preventing the flow of air 80 from the pipe into the ends of the cylinder during the time the relief valve is occupying its open position.

85 In testimony whereof I have signed this specification.
